PHILANDER LEEK, OF HARTFORD, CONNECTICUT.

Letters Patent No. 85,108, dated December 22, 1868; antedated December 11, 1868.

IMPROVEMENT IN DOORS FOR CARRIAGES, &c.

The Schedule referred to in these Letters Patent and making part of the same.

To all whom it may concern:

Be it known that I, PHILANDER LEEK, of Hartford, county of Hartford, and State of Connecticut, have invented certain new and useful Improvements in "Landau-Carriage Door" or sash-support; and to enable others skilled in the art to make and use the same, I will proceed to describe its construction and operation, by referring to the drawings, in which the same letters indicate like parts in each of the figures.

The nature of this invention will be understood from the specification and drawings.

The object of this invention is to provide a firm support for the window-sash, both at its upper and lower ends, while the door is open or closed, independent from the carriage-frame, so that it may be lifted from the boxing in the lower portion of the door, in the ordinary way, and be firmly supported in its elevated or closed position at the upper and lower edges.

In the accompanying drawings—

Figure 1 is a side elevation of a carriage-door, hinged to a portion of the frame-work of the body or top of a carriage.

Figure 2 is also a side view, showing a portion of the frame-work composing a part of the top, which turns back or opens in opposite directions, to form an open carriage, showing the sash-supporter and the mode of its construction.

Figure 3 shows the sash-supporter detached from the door.

a represents a portion of a frame for the body of a carriage.

b is a recess into which the supporter *e* is compactly folded and firmly held by hinges or buts *d*.

The upright or side of this window or sash-supporter *e* is formed with three sides, (back and two sides.) The width of the opening in the lower end is

about the width of twice the thickness of the sash *e'*, while the width of the opening at the upper end is about equal to the thickness of the sash. The object of this diverging formation is for the purpose of allowing the sash to be lifted out of the boxing in the door, so that the upper edge or end will enter the top or horizontal portion of the supporter *f*, while the lower edge or end is pushed sidewise into a recess sufficient to sustain or hold the sash from dropping back into the said boxing formed in the lower part of the door.

The two parts, *e* and *f*, are hinged together at *g*, fig. 3, so that the horizontal piece *f* will close into the part *e* when the sash is dropped into the boxing of the door.

A catch or spring, *h*, is secured to the upright, *e*, near the union joint, which acts against the stud *i*, both to hold the part *f* open in a horizontal position, and to hold it in a closed position parallel with the part *e*.

Thus, the sash may be easily raised and lowered and be held firmly in a uniform position, and the door freely opened and closed, without the liability of breakage or otherwise being injured.

I believe I have thus shown the nature, construction, and advantage of this invention, so as to enable others skilled in the art to make and use the same therefrom.

What I claim, therefore, and desire to secure by Letters Patent, is—

The combination of the two parts, *e* and *f*, with the catch or spring *h*, or its equivalent, and the frame-work *a*, constructed and operating substantially as described.

PHILANDER LEEK. [L. s.]
